(57) **CLAIM**

The ornamental design for a battery charging station, substantially as shown and described.

DESCRIPTION

FIG. 1 is a perspective view of a battery charging station. FIG. 2 is a front view of the battery charging station. FIG. 3 is a back view of the battery charging station. FIG. 4 is a right side view of the battery charging station. FIG. 5 is the left side view of the battery charging station. FIG. 6 is a top side view of the battery charging station; and, FIG. 7 is a bottom view of the battery charging station. The broken lines in the drawings illustrate portions of the article that form no part of the claim.
